UNITED STATES PATENT OFFICE.

CONCETTINA MARCHESE AND ANTONIETTA MARCHESE, OF BROOKLYN, NEW YORK.

PROCESS OF INSERTING OPENWORK IN FABRICS.

1,313,198.

Specification of Letters Patent.

Patented Aug. 12, 1919.

Application filed September 7, 1916. Serial No. 118,903.

To all whom it may concern:

Be it known that we, CONCETTINA MARCHESE and ANTONIETTA MARCHESE, subjects of the King of Italy, both residing in the 5 city of New York, borough of Brooklyn, county of Kings, and State of New York, have invented a certain new and useful Process of Inserting Openwork in Fabrics, of which the following is a specification.

10 This invention is a method or process of producing open-work, lace, or embroidery patterns in such hosiery as is manufactured plain, or without such patterns or open-work portions.

15 It has been the practice, when open-work hosiery is desired, to weave the open-work portions directly into the hosiery as the process of weaving or knitting progresses in the manufacture of the hosiery. This can only

20 be done through the employment of a limited number of special attachments to hosiery legging machines during the knitting operation. The object of the invention is to provide a process whereby open-work designs

25 may be applied to hosiery after said hosiery has been finished plain, and in such manner that the elasticity and durability of the hosiery are not impaired.

30 Features of the invention, other than those specified, will be apparent from the hereinafter detailed description taken in conjunction with the accompanying drawing.

35 In the accompanying drawing we have shown, diagrammatically, three consecutive steps in the production of an open-work portion in a stocking, which steps are carried out in accordance with the present invention. It will be understood, however,

40 that the stitches employed may be varied to produce different patterns, and that the showing made is, therefore, illustrative, only, and does not define the limits of the invention.

45 Figure 1 shows a portion of a drop-stitch fabric, such as is generally employed in hosiery construction, showing the first step in the process. The fabric is shown on a greatly enlarged scale to illustrate the 50 weave; and

Figs. 2 and 3 indicate subsequent steps in the process.

As hosiery is generally constructed from a drop-stitch fabric, we have chosen, for the 55 purpose of illustration, the application of

the invention to such environment. As is well known, a drop-stitch fabric embodies a large number of interlocked loops arranged in series, so that the consecutive loops of each series are locked in position by the next preceding loops. If any one loop becomes broken or disrupted, the well known "run" occurs. That is to say, if one of the loops is broken, the next adjacent loop of the series is released, and this, in turn, releases the next loop, and so on, so that the loops become straightened out, lose their interlocked relation, and that portion of the stocking where the run has occurred embodies, merely, a plurality of parallel threads which are readily discernible from the remainder of the fabric and are generally considered a detriment in stocking construction, usually occurring through excessive strain brought about by wear.

75 This well known disadvantage best illustrates the starting point of the present process, since the first step in the process is to produce a run in that portion of the stocking where it is desired to position the open-work. This is clearly shown in Fig. 1, the loop *a* having been cut at *a'* to release the adjacent loops for the desired distance. In other words, the first step in the process consists in cutting one of the loops and allowing the run to progress as far as the loop *b*, the distance between the loops *a* and *b* being the desired length of the open-work portion to be produced. The transverse threads which previously formed the loops which were maintained in interlocked relation by loop *a* become straightened out and form the substantially parallel threads *c*.

80 The subsequent steps in the process consist in reinforcing loop *b* so that "running" beyond the predetermined point is precluded, reinforcing the loops at the other end of the run, including broken loop *a*, and gathering together, generally in series, the threads *c* to produce the open-work portion. 85 These subsequent steps may be accomplished either by machinery or by hand, and an unlimited variety of open-work designs or patterns may result, which patterns or designs may be of any color desired and may be 90 produced in thread either the same in texture and material as that of the stocking or of different texture and material.

95 For the purpose of illustration, a showing is made as accomplished by hand, although 100

it will be manifest that the same result could be produced mechanically. The path which the operator may cause the working thread to take is shown in heavy lines in Fig. 2, where said working thread is designated, generally, D. The first step preferably consists in starting with the thread at d, and making a few cross-stitches, at E, to lock loop b and the adjacent loops of its series against further running. The thread is then carried by a lead e to the remote side of an adjacent series of loops, and the parallel threads c are caught up in series by a plurality of loops f formed in the working thread D, as shown. Thread D is then carried by a lead g into juxtaposition with the loop a, and a few cross-stitches are made at this point, designated G, to lock loop a in place. The thread is then led to the remote side of the other adjacent series of loops and a plurality of loops h, corresponding to loops f, and similarly positioned, are formed, the working thread D being thereafter preferably returned to point E and a couple of stitches taken to preclude inadvertent releasing of the free end d' of working thread D. In order that the functions of the stitches of working thread D may be clear, these stitches are shown as very loose, *i. e.*, not pulled tight, in Fig. 2, whereas, in Fig. 3 the stitches f and h are shown as pulled tight to draw the threads c, which they embrace, into intimate relation to provide a distinct open-work portion, as differentiated from the remainder of the fabric, where all of the transverse threads are spaced at substantially equal distances.

The foregoing manner of manipulating working thread D may be accomplished by hand, with either a single or a double thread, the operator employing a needle. This manner of producing the desired end is the simplest method of producing the open-work portions and, at the same time, precluding further runs in that portion of the stocking. This simple manipulation of the thread is chosen for illustrative purposes, although it will be manifest that the cross-stitching at E and G may be of an ornamental nature; that is to say, it may partake of the form of a star, group of leaves, an arrow-head, clocks, or other elements of design. Moreover, working thread D may be worked into lace in the open-work portions thus formed either by hand or machinery. In this manner, innumerable designs and patterns may be produced.

It will, of course, be understood that the process may be repeated at different points in the stocking, to collectively produce the desired artistic effect. It will further appear that the open-work portion may extend over more than three series of drop-stitches, if wider open-work portions are desired. This may be accomplished through

the use of one or a plurality of working threads, the manipulation of which may be carried out in various ways without departing from the spirit of this invention.

It will appear that, from the very nature of the production of the open-work portions as described, the elasticity of the stocking, as a whole, is not in the least impaired, and, as the drop-stitches adjacent the runs initially produced are adequately caught up during the process, the progression of such runs beyond the predetermined points is precluded. No material is actually cut out of the stocking, so that said stocking retains all its original strength and elasticity and is, in fact, rendered stronger by the working thread and embroidery or lace-work produced thereby.

In the manipulation of thread D as described, the first stitch taken is that at the finishing end of the run, but it will be manifest that, if desired, the first stitch might be made at the point where it is desired to start the run, the run thereafter produced, and a few stitches taken after it has progressed for the desired distance, said last-mentioned stitches being to stop the run at the proper point and preclude its progressing farther. The stitches for gathering together the threads to produce the open-work may next be applied.

The present invention, while particularly adapted for producing open-work in finished hosiery, may be carried out in any fabric wherein a run may be produced, and is not limited entirely to the hosiery art. Thus, through the practice of the present invention, open-work portions may be provided in sweaters, crocheted fabrics, fabric gloves, and various other articles which will be manifest to those skilled in the art. The present invention, therefore, is not restricted to the specific environment set forth or to the particular manipulation of the stitches specifically described and shown in the drawings, but is to be understood to be as broadly novel as is commensurate with the appended claims.

Having thus fully described the invention, what we claim as new, and desire to secure by Letters Patent, is:

1. The method of producing open-work in fabrics which consists in producing a run in a drop stitch or knitted fabric, checking the run at the opposite ends thereof to preclude said run from extending beyond predetermined limits, and gathering the threads which extend across said run to form the open-work portion.

2. The method of producing open-work in fabrics which consists in producing a run in a drop stitch or knitted fabric, checking the run at the opposite ends thereof, by drawing the stitches of the fabric together at these points, to preclude said run from

extending beyond predetermined limits, and gathering the threads which extend across said run to form the open-work portion.

3. The method of producing open-work in drop stitch fabrics which consists in producing a run in the fabric, encircling said run with stitching for the purpose of checking the run to preclude it from extending beyond predetermined limits, and leaving the stitches which extend across the run intact.

4. The method of producing open-work in fabrics which consists in producing a run in a drop stitch or knitted fabric, encircling said run with stitching for the purpose of checking the run to preclude said run from extending beyond predetermined limits, and gathering the threads which extend across said run to form the open-work portion.

5. The method of producing open-work in drop stitch fabrics which consists in producing a run in the fabric, checking said run at its opposite ends to preclude it from extending beyond predetermined limits, and leaving the stitches which extend across the run intact.

6. The method of producing open-work in fabrics which consists in producing a run in a drop stitch or knitted fabric, providing said run with encircling embroidery to preclude the run from extending beyond predetermined limits, and gathering the threads which extend across said run to form the open-work portion.

7. The method of producing open-work in fabrics which consists in producing a run

in a drop stitch or knitted fabric, inserting in the fabric, at the end of the run, a plurality of stitches to check the run, and gathering the threads which extend across said run to form the open-work portion.

8. The method of producing open-work in fabrics which consists in parting one of the stitches in a drop-stitch fabric, producing a run therein, checking the run at its opposite ends to preclude the same from extending beyond predetermined limits, and gathering the stitches which extend across said run to produce the open-work portion.

9. The method of producing open-work in fabrics which consists in producing a run in a drop stitch or knitted fabric, checking the run at its opposite ends to preclude said run from extending beyond predetermined limits, and positioning stitches within the run in such manner as to produce the open-work portion.

10. The method of producing open-work in fabrics which consists in disrupting one of the threads in the rib of a ribbed fabric to produce a run longitudinally of the rib, applying stitches to the rib at the opposite ends of the run to preclude said run from extending beyond predetermined limits, and gathering the threads which extend across said run to form the open-work portion.
